DESIGN FOR AN ELECTRICAL PLUG DEVICE

Ralph B. Hill, Bridgeport, Conn., assignor to
Electric Plug, Inc., Bridgeport, Conn., a cor-
poration of Connecticut

Application April 28, 1934, Serial No. 51,576

Term of patent 7 years

To all whom it may concern:

Be it known that I, Ralph B. Hill, a citizen of the United States, residing at Bridgeport, in the county of Fairfield, and State of Connecticut, have invented a new, original, and ornamental Design for an Electrical Plug Device, of which the following is a specification, reference being had to the accompanying drawing, forming part thereof.

In the drawing:

Fig. 1 is a side elevation of an electrical plug device, showing my new design, the prongs being shown in dotted lines.

Fig. 2 is a front elevation; and

Fig. 3 is a top plan view, the rectangular ele-
ments shown in the central portion of the top
representing prong openings through which the
plug-in prong members mounted in the device
project, these prong members being shown in
dotted lines.

I claim:—

The ornamental design for an electrical plug
device, as shown and described.

Signed at Bridgeport, in the county of Fairfield
and State of Connecticut, this 19th day of April,
1934.

RALPH B. HILL.
